UNITED STATES PATENT OFFICE.

WILLIAM A. KILMER, OF NEWBURG, NEW YORK.

DESIGN FOR A FENCE-PANEL.

SPECIFICATION forming part of Design No. 23,975, dated January 29, 1895.

Application filed December 11, 1894. Serial No. 531,512. Term of patent 14 years.

To all whom it may concern:

Be it known that I, WILLIAM A. KILMER, a citizen of the United States, residing at Newburg, in the county of Orange and State of New York, have invented and produced a new and original Design for Panels for Fences; and I do declare the following to be a full, clear, and exact description of the same, reference being had to the accompanying drawing forming a part thereof.

The figure shows a plan or a face view of a fence panel containing the design.

The leading feature of the design consists of a panel for fences composed of horizontal strands and vertical pickets each picket having substantially parallel sides which are connected together by transverse, oblique bars.

The letter A represents the pickets. These pickets are made of a strip, which has the substantially parallel sides α connected by the transverse, oblique bars α' . Such bars are arranged so that the spaces among them are triangular shaped, as shown in the drawing. The ends of these pickets A are turned about themselves so as to make the curved ends α^2 .

What is claimed is—

The design for a panel for fences, substantially as shown and described.

In testimony whereof I affix my signature in presence of two witnesses.

WILLIAM A. KILMER.
